Primary Examiner—Wallace R. Burke*Assistant Examiner*—M. H. Tung*Attorney, Agent, or Firm*—Wells, St. John, Roberts, Gregory & Matkin[57] **CLAIM**

The ornamental design for a computer mouse, as shown and described.

DESCRIPTION

FIG. 1 is a top, rear perspective view of a computer mouse showing my new design according to a first embodiment having two activation buttons;

FIG. 2 is a bottom view thereof;

FIG. 3 is a top view thereof;

FIG. 4 is a right side view thereof, the left side view being a mirror image thereof;

FIG. 5 is a rear view thereof;

FIG. 6 is a front view thereof;

FIG. 7 is a top, rear perspective view of a computer mouse showing my new design according to a second embodiment having three activation buttons;

FIG. 8 is a top view thereof; and,

FIG. 9 is a rear view thereof.

The right side view of the second embodiment being identical to that shown in FIG. 4, the left side view being a mirror image thereof, the bottom view being identical to that shown in FIG. 2, and the front view being identical to that shown in FIG. 6.
